(57) **CLAIM**

The ornamental design for a fishing tackle holder as shown and described.

DESCRIPTION

FIG. 1 is a top/front perspective view of a fishing tackle holder embodying my new design;

FIG. 2 is a bottom/rear perspective view thereof;

FIG. 3 is a front view thereof;

FIG. 4 is a rear view thereof;

FIG. 5 is a top view thereof;

FIG. 6 is a bottom view thereof; and

FIG. 7 is a left-side view thereof; and,

FIG. 8 is a right-side view thereof.

The broken lines show portions of the fishing tackle holder that form no part of the claimed design.
